[57] CLAIM

The ornamental design for an apertured panel for a combined vehicular tape player and radio or the like, as shown and described.

DESCRIPTION

FIG. 1 is a top, front and right side perspective view of an apertured panel for a combined vehicular tape player and radio or the like showing my new design;

FIG. 2 is a top plan view thereof, the bottom being a mirror image;

FIG. 3 is a front elevational view thereof; and

FIG. 4 is a left side elevational view thereof.

The broken line showing of the cabinet is for illustrative purposes only and forms no part of the claimed design.
